TUBE CLAMP

Robert R. Harrison, North Hollywood, Calif., assignor, by meane assignments, to Bendix Aviation Corporation, South Bend, Ind., a corporation of Delaware

Application October 10, 1941, Serial No. 414,417

2 Claims. (Cl. 174—40)

This invention relates to tube clamps, and more particularly to tube clamps which are provided with means to electrically ground any tube or conduit held in the clamp.

Some of the structures herein disclosed are claimed in my divisional application, Serial No. 620,208, filed October 4, 1945.

One object of the invention is to provide a tube clamp having an electrical grounding strip provided with a curved portion to accommodate vibration well within the elastic limit of the strip.

Another object of the invention is to provide a tube clamp with an electrical grounding strip which is rigidly aligned with the metal loop forming the main element of the clamp.

Other objects and advantages of the invention will be apparent in the following description and claims taken in connection with the accompanying drawing in which:

Figure 1 is an isometric view of a tube clamp embodying the invention, with a segment of a tube clamped therein;

Figure 2 is an elevation of a segment of the tube clamp of Figure 1 showing a portion of the cushion of the clamp and the electrical grounding strip overlying the cushion;

Figure 3 is an elevation of a portion of the clamp of Figure 1 in its final form, showing expansion bend in the electrical conducting strip;

Figure 4 is an isometric view of a modification of the invention showing one end of the electrical grounding strip bent over the cushion element; and

Figure 5 is an isometric view of a portion of the strip of the loop of Figure 4, showing the grounding strip welded to the metal loop, and showing the cushion in dotted outline.

For the present purposes, it will be stated that the clamp is used to hold conduits to any structural member of the vehicle in which they are mounted. They are particularly adapted for use in airplanes, and for this purpose a cushion element must be provided to prevent injury to the clamped tube due to the intense vibrations found in airplanes. However, it has been found that static charges accumulate on conduits held in an insulating material such as is commonly employed as the cushion element, and electrical grounding strips are employed to remove the static charges, which present a fire hazard, as well as an interference to radio operation, when they discharge across an air gap.

The clamp of Figure 1 comprises a metal strip 10 of aluminum, or where great strength is re-

quired, of stainless steel. The metal strip 10 is bent to a rounded shape so as to form a loop to encircle any tube or conduit 12 which may be held therein. One end 14 of the strip 10 is bent at right angles to the body of the strip, so as to be parallel with the other end, permitting a screw 16 to be passed through both ends to secure the clamp as a whole to any member. The clamp is provided with a cushion 18 which is preferably of a resilient material such as the commonly available synthetic rubber-like materials which are resistant to oil and gasoline. Since such cushions are usually insulators, a grounding strip 20 is secured to the loop metal 10, and overlies the cushion 18 so as to electrically ground any conduit to the metal of the clamp loop 10.

The loop strips 10 are first formed in a flat position, and the cushion material 18 is vulcanized or bonded to the strip 10 by methods well known to the art. The grounding strip 20 is then secured to the strip 10 by a hollow rivet 22 passing through hole 24 in one end of strip 10.

The construction thus far described is common in the tube clamp art, but under severe operating conditions where vibration is intense, it has been found that the grounding strip 20 tends to swivel on its rivet 22 and work off of the cushion 18 under which condition it no longer grounds the conduit 12. Further, it has been found that the vibration causes minute reversals of stress in grounding strip 20 in a direction to cause alternate tension and compression. Such reversals of stress set up a fatigue condition which sometimes causes the conducting tag 20 to crack near its rivet 22.

Both of these undesirable conditions are eliminated in the present invention by vulcanizing or bonding the strip 20 to the cushion 18, and as has already been explained the cushion 18 is bonded to the strip 10. The strip 20 is bonded to the cushion 18 while the entire clamp is in a flat position as shown in Figure 2. When the clamp is bent to its final form, the strip 20 will be on the inside of the loop and consequently will buckle in any free region to accommodate the lesser radius during the bending. This buckle or crimp in strip 20 is shown in Figure 3 at 26.

The construction described provides an expansion bend 26 in the final clamp which will accommodate stresses in the strip 20 which are well within the elastic limit of the material in the strip. Further, the bonding of the strip 20 to cushion 18 insures that it will not swivel about

its rivet and therefore work out of contact with any conduit 12 held in the clamp.

The clamp of Figure 4 comprises a loop of metal 40 formed in a shape similar to strip 18 of Figure 1. A cushion 42 overlies the curved portions of strip 40, and a grounding tag 44 electrically connects any conduit with the strip 40. As seen in Figure 5, the strip 44 is welded to strip 40 by a spot weld 46 before the cushion element 42 is applied to the assembly. After bonding the cushion 42 to strips 40 and 44, the outer end of the strip 44 is bent upwardly and then over to overlie a portion of cushion 42, as shown in Figure 4.

The construction of Figures 4 and 5 has the same advantages as the construction of Figures 1, 2 and 3. Since the grounding tag 44 is welded to the loop metal 40 rather than riveted, it is impossible for any swiveling action to take place such as will allow movement of the tag 44 off of cushion 42. The bend in grounding strip 44 at the region 48 gives a sufficient arc or curvature in the tag 44 so as to accommodate any reversals of stress well within the elastic limit of the ma-

terial. Thus both embodiments of the invention insure freedom from fatigue cracks, and insure that the grounding strip will always overlie the cushion.

5 Although this invention has been described with reference to particular embodiments thereof, it is not limited to these embodiments or otherwise except by the terms of the following claims.

I claim:

10 1. A tube clamp comprising a loop of metal having holes in the ends, a cushion of rubber-like material bonded to the inner surface of the loop, and a grounding strip riveted to the hole in one end of said loop and bonded to the inner surface of said cushion.

15 2. A tube clamp comprising a loop of metal, a cushion of rubber-like material bonded to the inner surface thereof, and a grounding strip secured to the metal loop and bonded to the inner surface of said cushion and having a pronounced bend therein to accommodate fatigue stresses.

ROBERT R. HARRISON.
